UNITED STATES PATENT OFFICE

2,423,207

ICE-CREAM CABINET

Renwick J. Sharp, Guatemala, Guatemala.

Application October 6, 1944, Serial No. 557,422

1 Claim. (Cl. 220—47)

1

This invention relates to improvements in ice cream cabinets and the like.

Hitherto it has been the usual practice to construct ice cream cabinets with horizontal tops and so to arrange their chambers as to support the contained receptacles in upright positions. The result is that the attendant finds it necessary to bend the body in an uncomfortable manner to reach down into the containers to obtain access to their contents, particularly when it becomes necessary to reach down to the bottom portions of nearly empty containers.

Another defect of these structures has resided in the fact that in opening their lids the operator must use one of his or her hands, which it is often inconvenient for an attendant to do, owing to having both hands in use when serving foods to customers.

Also, due to the upright position in which the food-containing chambers of the cabinets have heretofore been arranged, when the delivery-man deposits the cartons of ice cream into these chambers he is apt to drop them with a sufficient impact to cause the cartons to rupture, whereas, if the cartons descended along inclined surfaces this danger would be obviated.

It is the object of this invention to overcome the above mentioned defects in a simple, inexpensive manner.

Other objects, advantages and features of invention will hereinafter appear.

Referring to the accompanying drawing, which illustrates what is at present deemed to be a preferred embodiment of the invention,

Fig. 1 is an end elevation of a multiple ice cream cabinet, parts being shown in section in order to illustrate interior structures more clearly.

Fig. 2 is a plan view of the upper side of the cabinet end portion shown in Fig. 1, the direction in which the observer is looking being indicated by the line 2—2 on Fig. 1. Parts of the cabinet not needed to illustrate the invention are broken off.

Fig. 3 is a front elevation of the structure shown in Fig. 2, viewed from line 3—3 of the latter view.

Fig. 4 is a rear elevation of the end portion of the cabinet shown in Figs. 1 and 2, viewed from line 4—4 of the former view, the cabinet being broken off adjacent to the unit shown.

Fig. 5 is an enlarged sectional detail taken on line 5—5 of Fig. 1.

Referring in detail to the drawing, the cabinet body 7 differs from the usual construction in that each of its containing chambers 8 are inclined

2

as shown with its lower end near the rear side of the cabinet and its upper end opening out in the lower, front part of the top surface plate 9 of the cabinet, said surface plate being downwardly inclined from rear to front. This inclination of cabinet top surface and of container chambers enables the attendant more conveniently to reach and remove the contents of the containers 10 in said chambers, particularly when the containers become nearly empty.

Communicating with the rear side portion of the chamber 8 is shown a conventional refrigerating means 8x.

Each containing chamber 8 is furnished with a 15 sliding cover 11 to the upper end of which is connected at 12 one end of a flexible tractive connection 13, said connection passing over an antifriction pulley 14, which is rotatably mounted in any suitable manner, being shown furnished 20 with a pintle 15 carried by a yoke 16, said yoke having a shank 16a extending loosely through a downwardly deflected part 17 of the lining or cover plate 8, said plate having also a downwardly directed flange 18 to which said shank 25 is adjustably attached, as for example by screw-threading thereinto. This screwthreaded connection permits the pulley 14 to sway from full line to dotted line position as shown in Fig. 4 when the foot-operable crank is operated to shift 30 the sliding cover, the flanges 16x of the yoke contacting the deflected part 17 to limit to an extreme movement such swaying action.

Said part 17 defines a recess which countersinks the pulley to a considerable extent so that 35 a large, friction-reducing pulley may be used without its presence causing an objectionable projection.

The lower run 13a of the connection is secured to the free end of a swingable operating arm 20, 40 the opposite end of said arm or movement multiplying lever being fixed to the rear end of a horizontal rock shaft 21, bearings 22 and 23 for which are carried by the cabinet body 7. The front end of said shaft 21 has fixed to it the aforementioned foot-operable crank 24 partly housed 45 in a suitable alcove 25. By the arrangement above described the foot-operable crank 24 may be utilized to cause the connection 13, 13a to pull the cover 11 up the inclined surface on which it rests, thus uncovering the chamber 8 with less movement of the crank 24 by the foot than the distance traversed by the lid in uncovering the opening in the chambers 8 hereinafter described. When the operator removes his foot 50 from the crank 24 said cover will gravitate back

to the closed position, this movement being assisted by a pair of springs 26, these springs being located in grooves 27 positioned laterally in the cover guides 28, being anchored as shown in Fig. 2.

The foot-operable crank 24 is shown located so close to the lower end of the cabinet that it is operable by the toe portion of the foot of a person while the heel of the same foot is resting upon a floor which supports the cabinet.

In order to provide for obtaining access to the chamber 8 and container 10 therein without always operating the crank 24, the slideable cover 11 is provided with a spacious opening 30 which is normally closed by a lid 31 hinged to the upper part of the cover at 32, an elastic bumper 33 arresting the upswing of said cover in the position indicated in Fig. 1, after it passes the center of gravity in moving to its open position.

It should be understood that the present disclosure is for the purpose of illustration only and that this invention includes all modifications and equivalents which fall within the scope of the subject matter claimed.

What is claimed is:

In a cabinet having its top wall inclined downwardly toward the front and provided with a material receiving chamber opening through said top wall, a cover slideable on said top wall from a forward chamber-closing position to a rearward position for opening said chamber, a rock shaft journaled horizontally on the lower part of said cabinet, a foot-operable crank fixed to one end of said shaft and disposed at the front of the cabinet, a lever having a radial length substantially greater than that of said crank fixed to the opposite end of said rock shaft and arranged to

swing in a vertical plane rearwardly of the cabinet, a flexible element trained for movement over the upper rear portion of the cabinet and connecting the free end of said lever with said slideable cover whereby foot-operated movement of said crank will cause greatly increased arcuate movement at the free end of said lever to pull the flexible element sufficiently to effect full opening slide of the cover, means yieldingly urging said cover to forward closed position, said top wall being provided with a channel directed forwardly from its rear wall and having undercut grooves at each side of the channel, said cover being slideable in said channel and grooves, a tension spring fastened in each of said grooves and to the cover to resiliently urge the cover to chamber-closing position, said cabinet having a recess in its lower front portion within which said foot crank is housed, and a pulley rotatably mounted on the upper rear portion of the cabinet to guide said flexible element thereover.
